RETRACTABLE SPRAY DEFLECTOR

Bradford W. Powers, San Diego, Calif., assignor
to Consolidated Vultee Aircraft Corporation,
San Diego, Calif., a corporation of Delaware

Application February 20, 1947, Serial No. 729,766

10 Claims. (Cl. 244—106)

1

This invention relates to improvements in flying boat hulls and more particularly to a retractable spray deflector adapted to be incorporated in flying boat hulls both of rather conventional type and in highly streamlined hulls.

In the past, the air speed of flying boats has been considerably reduced by the necessity for designing the hull of the flying boat on hydrodynamic principles, since the hull has to be so designed that it will serve as an efficient planing surface for the aircraft during take-off. Such hydrodynamic lines are frequently very inefficient from an aerodynamic standpoint and extensive research has been made in an endeavor to properly integrate the most efficient aerodynamic and hydrodynamic features in a flying boat hull which would give maximum performance on the water and in the air.

Recently, the tendency to streamline aircraft fuselages has been extremely marked and efforts have been made to conform to this tendency in the design of the flying boat hull. However, the essential nature of a flying boat hull has always been a limiting factor.

As is well known in the art conventional flying boats to achieve a hydrodynamically sound construction require the bottom, or water contacting surfaces, to meet the freeboard surface of the hull in such a fashion that a sharp edge is effected. This sharp edge extending into the air-stream produces a turbulent condition and is thus a source of drag. Nevertheless prior flying boat hulls have found it necessary to utilize this type of construction since when the hull of a flying boat is passing through the water preparatory to take-off, the sharp edge construction serves to deflect the spray developed by the passage of the boat through the water and prevents it from buffeting the propellers and control surfaces of the aircraft. The sharp edge construction also serves as a stabilizing element in that it provides directional stability for the hull of the boat and inhibits any tendency there may be to hunt in the water. The sharp edge construction also serves, to a certain extent, to eliminate "porpoising" or the nosing down tendencies which flying boat hulls frequently exhibit.

To permit a flying boat hull to be designed in as complete conformity to aerodynamic principles as is possible, while retaining its hydrodynamic efficiency, the retractable spray deflector which is the subject of the present invention has been designed. By use of the retractable spray deflector hulls which possess a maximum of aerodynamic efficiency may be designed for

2

incorporation in flying boats. The retractable spray deflector is incorporated in the hull approximately along the line of the hull where the sharp edge would customarily be located. When the boat is about to take off the retractable spray deflector is extended from its housing within the hull and during the take-off period functions to afford a hull operating in the same manner as and having the effectiveness of a conventional hull with its sharp edge construction. When the flying boat is airborne the spray deflector is retracted within its housing and the flying boat hull assumes its maximum aerodynamic efficiency.

It is one object of the present invention to provide a retractable spray deflector for flying boat hulls which can be extended into the water during the take-off and landing periods and can be retracted into the hull of the flying boat when the flying boat is airborne.

It is another object of this invention to provide a retractable spray deflector for flying boat hulls which are designed to such aerodynamic standards as would inhibit the proper functioning of the boat hull in the water unless such a retractable spray deflector were incorporated in the hull.

Other objects and advantages of the present invention will become apparent from a reading of the appended specification and the accompanying drawings in which:

Figure 1 is a perspective view showing the underside of a rather conventional flying boat hull which incorporates the retractable spray deflector;

Figure 2 is a front elevational view of the hull shown in Figure 1;

Figure 3 is a front elevational view of a highly streamlined flying boat hull possessing maximum aerodynamic efficiency which has embodied therein a retractable spray deflector adapted to secure hydrodynamic effectiveness for the aerodynamically efficient hull;

Figure 4 is a vertical sectional view through the hull of the flying boat shown in Figure 1 which shows the installation in the hull of a retractable spray deflector constructed in accordance with the present invention;

Figure 5 is a vertical sectional view taken on line V—V of Figure 6;

Figure 6 is a longitudinal sectional view showing the installation of the retractable spray deflector in its housing and indicating the position which it will assume in its extended phase and, in phantom, the position which it will assume when retracted;

Figure 7 is a perspective view showing the spray deflector in its extended position; and

Figure 8 is a perspective view showing the spray deflector in its retracted position.

There is shown in the drawings (Figure 1) a typical flying boat 10 having a wing 11 and power plants 12 mounted in said wings adapted to propel said flying boat through the air. The fuselage 13 of the flying boat 10 is unique in that the hull bottom 14 which forms the lower portion of the fuselage 13 does not meet the side walls of the fuselage to effect a sharp edge as is conventional. At the points where the sharp edge would ordinarily occur there are installed retractable longitudinally elongated elements or members 15 adapted to serve in the place of the conventional construction.

The embodiment of such retractable spray deflectors 15 will permit a flying boat hull of greater aerodynamic effectiveness but will, nevertheless, insure that the hull will be hydrodynamically stable during the take-off and landing periods.

In Figure 3 there is shown a radically streamlined flying boat 16 which comprises a wing 17 and a generally V-shaped fuselage portion 18 which is also intended to serve, to a certain extent, as an auxiliary aerodynamic lifting surface in conjunction with the wing 17. Hull bottom 19 of fuselage 18 is so constituted that it possesses a modicum of hydrodynamic efficiency. However, the incorporation of retractable spray deflectors 20, constructed in accordance with the present invention, serves to augment the hydrodynamic characteristics of the hull bottom 19 and renders the flying boat a hydrodynamically as well as aerodynamically sound aircraft.

There is shown in Figure 4 a vertical sectional view of the flying boat hull of Figure 1. The exterior skin 21 of the fuselage 13 is supported by an internal bulkhead 22 which has cut there-through an oblique cut 23 which forms a receptacle for the housing 24 of a typical retractable spray deflector 32. It is to be understood that such openings are cut in adjacent bulkheads to permit the installation of the housing 24 throughout the length of the hull.

The retractable spray deflector housing 24 comprises side walls 25, a top wall 26 and end walls 27. The housing is isolated from the interior of the fuselage 13 and is of water proof construction. Formed in the lower ends of side walls 25 are integral flanges 28 which provide attachment points by means of which the housing is attached to the fuselage. That portion of the bulkhead 22 which provides a receptacle for the housing is strengthened by gusset plates 29 which permit the bulkhead to absorb the stresses placed upon it by the housing and the spray deflector.

Adapted to be retracted into housing 24 but shown, for purposes of clarity, in the extended position in Figures 4, 5 and 6, is the retractable spray deflector 32. A multiplicity of link members 33 which are pivotally secured at their upper ends by means of shafts 34 passing through the walls 25 of housing 24 serve as suspension members for the retractable spray deflector 32. The upper ends of the links 33 have formed thereupon stop plates 30 which prevent the movement of the spray deflector beyond its fully extended position and which seat on the inside of top wall 26 of spray deflector housing 24. The lower ends of links 33 have stop plates 31 formed thereupon and integrally therewith which seat on the top wall 40 of retractable spray deflector 32 and which serve to prevent

over-travel of the spray deflector 32. The lower portions of the links are pivotally connected to triangular mountings lugs or plates 36, as by means of shafts 35 passing through the lower portion of said links and the upper portion of said plates. The lower portion of mounting plates or lugs 36 is secured to the upper portion of the retractable spray deflector 32. The pivotal suspension of the retractable spray deflector 32 upon links 33 permits the spray deflector 32 to be swung upon shafts 34 and 35 from a retracted position within the housing 24 to an extended position outboard of the fuselage 13 and hull bottom 14. The retractable spray deflector 32 comprises a roughly rectangular longitudinally extended closed box-like member which is formed by side walls 37, top wall 40, oblique rear end 38, vertical front wall 39 and a bottom plate 42 which is adapted to conform to the exterior configuration of the hull bottom 14 of fuselage 13. Bulkheads or stiffeners 43 upon which the various walls of the spray deflector 32 are assembled provide structural rigidity to the spray deflector 32.

The rear wall 38 of the retractable spray deflector 32 is formed at an oblique angle to permit the bottom plate 42 to seal the opening in the hull bottom when the spray deflector 32 is in its fully retracted position. As can be seen from the drawings, the rear wall 38 is extended rearwardly of the opening in the hull bottom 14 of the fuselage 13 when the spray deflector is dropped into its functioning position. When the spray deflector 32 is retracted into the housing 24 the oblique rear wall 38 of the spray deflector 32 permits the bottom plate 42 to seal off the opening in the hull bottom 14 of fuselage 13. The sealing of the hull bottom 14 of fuselage 13 by means of the bottom plate 42 of spray deflector 32 prevents turbulence and eliminated parasitic drag when the aircraft becomes airborne which would occur if the openings were not sealed.

When the spray deflector 32 is in its extended position considerable side loads will be borne by its structure and it is conceivable that it might possibly become so bound against the interior structure of housing 24 that retraction or extension might become difficult. To cut down the possibility of such binding there is provided a series of rubbing or chafing strips 44 which are mounted on the upper edge of the retractable spray deflector 32 and would materially reduce the frictional components which will be encountered during the operation of the spray deflector. Pivotedly mounted within the spray deflector housing 24 is an actuating means 45 which may conceivably be either a hydraulic or electric jack having a cylinder 46 and a piston rod 47 which extends into the receptacle formed by the interior of the housing 24. The extreme end of the piston rod 47 is pivotally connected at 48 to one end of retractable spray deflector 32 by means of flanges 49. Prior to take-off the extension of piston rod 47 will cause the spray deflector 32 to swing rearwardly and downwardly on links 33, bringing spray deflector 32 into its extended position to break the continuity of the bottom surface of the hull, as shown, and increasing the hydrodynamic efficiency of the flying boat hull during the take-off period. Once the aircraft is airborne the retraction of piston rod 47 will swing the spray deflector 32 upwardly and inwardly on links 33 into the interior of housing 24. Thus the aerodynamic efficiency of the hull is in no

way impaired by the retractable spray deflector 32.

There is thus provided a retractable spray deflector which is designed to impart to a flying boat hull of streamlined conformation hydrodynamic characteristics which would be lacking if such a spray deflector were not embodied in the hull. It is, of course, obvious that the embodiment shown in the drawings and discussed in detail in the above specification has been utilized to illustrate the manner of construction and mode of operation of the present invention and it is conceivable that changes may be made in details of construction which will still fall within the scope of the appended claims.

I claim:

1. A hull structure for a flying boat comprising a plurality of bodily movable elongated spray deflector members adapted to be housed within the hull on opposite sides thereof and extending in the direction of the length of the hull, means within said hull for suspending said spray deflector members for movement into and out of housed position said hull having elongated openings formed in either side thereof through which said spray deflector members are adapted to extend to break the continuity of the bottom surface of the hull, and actuating means located in said openings and having operative connections with said spray deflector members for movement thereof between housed and extended positions.

2. A hull structure for a flying boat comprising elongated spray deflector members disposed on opposite sides of the hull and extending longitudinally therealong, housings for said spray deflector members provided in said hull, pivoted mounting means within said housings for suspending said spray deflector members for movement bodily out of said housings to break the continuity of the bottom surface of the hull and actuating means carried by the hull within said housings and having operative connections with said spray deflector members for moving said members into and out of said housings.

3. A hull structure for a flying boat comprising elongated generally rectangular, box-like spray deflector members disposed on opposite sides of the hull and extending longitudinally therealong, housings for enclosing said spray deflector members provided in said hull and having one side thereof open, pivoted mounting means within said housings for suspending said spray deflector members for movement bodily out of said housings to break the continuity of the bottom surface of the hull actuating means mounted within said housings and having operative connections with said spray deflector members for moving said members swingingly into and out of said housings, and said elongated spray deflector members each having a bottom wall adapted to conform to the exterior profile of the hull and to close the open side of a housing.

4. In a hull for a flying boat, longitudinally extending housings formed within the interior of the hull and on each side thereof, swingably mounted elongated, generally rectangular, box-like spray deflector members adapted to be swung bodily into and out of said housings and acting when exteriorly positioned to break the continuity of the bottom surface of the hull, pivoted means within said housings for supporting said spray deflector members for swinging movement, actuating means for each of said spray deflector members mounted within said housings, and means operatively connecting said actuating

means to one end of its associated spray deflector member to permit the actuation thereof, said spray deflector members each having an oblique end wall provided at the end of the spray deflector member opposite the end to which said actuating means is connected.

5. In a hull for a flying boat, said hull having longitudinally extending, elongated openings formed in either side thereof, housings formed within the interior of said hull and having an open side juxtaposed to said opening, swingably mounted elongated, generally rectangular, box-like spray deflector members adapted to be housed in said housings and to be extended therefrom through said openings to break the continuity of the bottom surface of the hull, pivoted means within said housings for supporting said spray deflector members for movement bodily into and out of said housings actuating means for each of said spray deflector members mounted within said housings, and means operatively connecting said actuating means to one end of its associated spray deflector member whereby said spray deflector member may be actuated, said spray deflector members each having an oblique end wall provided at the end of the spray deflector member opposite the end to which said actuating means is connected, said spray deflector members also each having a bottom wall shaped to conform to the outer configuration of said hull whereby on retraction of the spray members into the housings the open sides thereof will be closed, said oblique end walls permitting movement of said bottom walls into position to close said open sides.

6. In a hull structure having the opposite sides thereof flat and which are formed into a V-shape, elongated spray deflector members disposed on opposite sides of the hull and extending longitudinally therealong, housings for wholly enclosing said spray deflector members provided in said hull, pivoted mounting means within said housings for swingingly suspending said spray deflector members for movement bodily out of said housings to project beyond the flat sides of the hull to break the continuity thereof, and actuating means carried by the hull within said housings and having operative connections with said spray deflector members for moving said members bodily into and out of said housings.

7. A hull structure for a flying boat comprising a plurality of bodily movable, elongated, generally rectangular, closed box-like spray deflector members adapted to be housed wholly within the hull on opposite sides thereof and extending in the direction of the length of the hull, pivoted means within said hull for suspending said spray deflector members for swinging movement, stop means provided on said pivoted means operative to limit the extent of swinging movement thereof, said hull having elongated openings formed in either side thereof through which said spray deflector members are adapted to extend to break the continuity of the bottom surface of the hull, and actuating means located in said openings and having operative connections with said spray deflector members for movement thereof between housed and extended positions.

8. In a hull for a flying boat, longitudinally extending housings formed in said hull and on each side thereof and opening to the exterior thereof, elongated, generally rectangular, closed box-like spray deflector members adapted to be positioned within said housings, link means in each of said housings for mounting said spray

deflector members for movement bodily through said openings in said housings to break the continuity of the bottom surface of the hull, said link means having a pivoted connection at one end to a wall of its housing and having its opposite end pivotally connected to a wall of its associated spray deflector member, said spray deflector members each having a bottom wall conforming with the exterior profile of the hull for closing the openings in said housing when said spray deflector members are positioned within their housings, and actuating means carried by the hull having operative connections with said spray deflector members for moving said members swingingly into and out of said housings.

9. In a hull for a flying boat, longitudinally extending housings formed in said hull and on each side thereof and opening to the exterior thereof, elongated, generally rectangular, closed box-like spray deflector members adapted to be positioned within said housings, link means in each of said housings for mounting said spray deflector members for movement bodily through said openings in said housings to break the continuity of the bottom surface of the hull, said link means each having a pivoted connection at one end to a wall of its housing and having its opposite end pivotally connected to the top wall of its associated spray deflector member, said spray deflector members each having a bottom wall conforming with the exterior profile of the hull for closing the openings in said housings when said spray deflector members are positioned within their housings, and actuating means carried by the hull having operative connections with said spray deflector members for moving said members swingingly into and out of said housings, said link means having stop means carried at each of their ends engageable with a housing wall and with the top wall of a spray deflector member to limit the extent of swinging movement thereof out of its housing.

10. In a hull for a flying boat, said hull having longitudinally extending, elongated openings formed in either side thereof, housings formed within the interior of said hull and having an open side juxtaposed to said opening, elongated, generally rectangular, closed box-like spray deflector members adapted to be positioned within

said housings and to be extended therefrom through said openings to break the continuity of the bottom surface of the hull, link members within each of said housings for supporting said spray deflector members for swinging movement bodily into and out of said housings, said link members each having a pivoted connection at one end to a wall of its housing and having its opposite end pivotally connected to the top wall of its associated spray deflector member, stop means carried at each end of said link members engageable with said housing wall and with said spray deflector member top wall to limit the extent of swinging movement of a spray deflector member out of its housing, actuating means for each of said spray deflector members mounted within said housings, and means operatively connecting said actuating means to one end of its associated spray deflector member whereby said spray deflector member may be actuated, said spray deflector members each having an oblique end wall provided at the end of the spray deflector member opposite the end to which said actuating means is connected, said spray deflector members also each having a bottom wall shaped to conform to the outer configuration of said hull whereby on retraction of the spray members into the housings the open sides thereof will be closed, said oblique end walls permitting movement of said bottom walls into position to close said open sides.
